SWITCH LEVER STOP

Homer E. Blair, McCool, Ind.

Application June 27, 1944, Serial No. 542,396

6 Claims. (Cl. 74—526)

1

The present invention aims to provide an improved form of stop for arresting the travel of the hand-operated lever of a railway switch stand.

An object of the invention is to provide means for minimizing the shock and thrust heretofore thrown through the switch-operating lever to the stand, its fastening, and bearings, which has caused loosening of the stand, rapid wear of its bearings, and damage to the equipment attached to the stand.

In the past, considerable damage has resulted to railway switch stands, and especially to low stands, from the manual throwing of the switch lever. The lever is pivoted to the stand, and the free outer end of the lever carries a relatively heavy weight. When the lever is forcibly thrown and the shank of the lever strikes a stop member, with the weight extending therebeyond, there is a terrific leverage tending to raise the housing in the air. Frequently, a switch man, especially in railway yards, will have a string of uncoupled freight cars coming toward him, and it is essential that he throw the switch lever in one direction for the first car, and rapidly throw the switch lever in the opposite direction to transfer the second oncoming car to a different track, and so on. Such very rapid throwing of the lever frequently resulted in injury to the housing of the switch mechanism, the breaking of the light in the event the switch stand was so equipped, and often causing long and expensive delay before the switch mechanism could be repaired so as to again operate. This formerly known type of switch lever with its associated stop member frequently loosened the stand, requiring tie plugs to be inserted and redriving of spikes, considerably shortening the life of the ties to which the housing is connected. With rapid throwing of a switch lever it is customary for the switchman to keep his hands, that is, both hands, on the lever weight at all times. Usually, one hand was beneath the weight, and frequently crushed fingers and crushed feet resulted.

With the foregoing in mind, it is an important object of the instant invention to provide a stop member for a switch stand which may be so located on a tie that contact between the lever arm and the stop member occurs immediately adjacent the weight on the end of the lever arm, to thereby minimize the shock to the housing and associated equipment by virtue of the throwing of the switch lever.

Another object of the instant invention is the provision of a switch lever stop having an up-

2

standing curvate stop portion to thereby give a high single contact point with the switch lever to avoid injury to a workman's hands, in the event one hand is disposed beneath the weight on the end of the switch lever.

Still another object of this invention is the provision of a stop member for a switch lever, which stop member is so constructed that it may be spiked to a tie with the spikes well within the tie and with the stop member disposed in substantially any desired location.

While some of the more salient features, characteristics and advantages of the instant invention have been above pointed out, others will become apparent from the following disclosures, taken in conjunction with the accompanying drawing, in which:

Figure 1 is a fragmentary plan view, with parts in section, of a switch stand with a pair of switch stops embodying principles of the instant invention associated therewith;

Figure 2 is a fragmentary elevational view of the structure of Figure 1;

Figure 3 is an enlarged plan view of my improved stop member; and

Figure 4 is a side elevation of the stop member of Figure 3.

Referring in detail to the drawings, 10 represents the housing of a conventional form of switch stand. This housing rotatably supports a shaft 12 to which is keyed or otherwise secured a switch-operating lever 14 having a weight 16 at the free end thereof. Within the housing is a crank 18 having a crankpin 20 adapted to operate a known type of slide member 22. This slide member is adapted to be shifted in a substantially straight-line motion along a guide 24. Member 22, when shifted, acts in a known manner through a pin 26, to shift a link 28, which is effective to rock a shaft 30 which carries a lever 32 pin-connected at 34, to a link 36 which in turn is suitably connected to the movable part of the track switch. These switch-operating parts are of well-known conventional form, and form no part of the present invention, thus need not be further shown or described.

Heretofore, when the operating lever 14 of a switch stand has been thrown, it has come to rest against a rigid fixed abutment usually forming part of, or secured to, the housing of the switch stand. In practice it has been found that the conventional stops heretofore used transmitted shocks to the switch stand and operating mechanism thereof. The chief object of the present invention is to eliminate such shocks and

strains. To this end I have devised the improved lever stop shown in detail in Figures 3 and 4.

The improved stop is formed of commercially obtainable flat steel or iron bar stock shaped to the configuration of Figure 4, so as to provide a flat base 38 which preferably has one or more holes 40 therein to accommodate fastening means such as lag screws, nails, or spikes 42, which are adapted to be screwed or driven into the supporting ties 44 on which the switch stand is mounted. At one end the stop is of curled formation constituting a slightly yieldable abutment portion, as indicated at 46, and the extremity 48 of the bar stock of which the stop is formed is bent around and extended down so as to contact the upper face of the base 38, as shown. Preferably the extremity 48 will be tack-welded to the base 38, thus integrally securing the curled extremity to the base by a body of weld metal 50. The curled formation of the abutment described endows it with a certain amount of inherent resiliency, so that when the switch lever 14 is thrown, for example, from the full-line position of Figure 2 to the dotted line position, the blow will be cushioned, thus minimizing shock and wear on the switch parts, with the result that the life of the switch stand and equipment connected thereto will be prolonged. It will be noted that the stop is not connected directly to nor interlocked in any manner with the switch stand structure proper, but is a separate piece mountable in any desirable location on a tie adjacent the switch stand structure. Further, it should be noted that the stop is not of the heretofore known type, which usually has spike holes on each side of the abutment portion, and frequently are attached to or interlocked with the base or housing of the switch stand, and thus are materially limited as to their location. Regulations require that spikes be driven into a tie at least two inches in from the edge of the tie, and ties are usually eight or nine inches wide across the working face thereof. With the instant invention, therefore, it is a simple expedient to locate the stop with the abutment portion adjacent the weight 16 on the switch lever, and yet the spikes that hold the stop member to the tie may be driven into the tie and be well inside the prescribed two-inch limit. This is quite clear from the showing in Figure 2 of the drawing.

It should also be noted, especially from the showing in Figure 2, that with the instant invention there is only point contact between the abutment and the switch lever. This, of course, is by virtue of the curvate formation of the abutment. This curvate formation, however, provides a distinct advantage over the flat-top abutments heretofore used, namely, an operator may get his hands very close to the abutment, without danger of crushing his fingers during the throwing of the switch lever.

From the foregoing, it is apparent that I have provided a novel stop member for association with a switch stand, which stop member may be located on the tie to suit local conditions without danger of splitting the tie by virtue of endeavoring to drive a spike too close to the edge of the tie. Positioning of the instant invention satisfies all requirements or regulations concern-

ing the driving of spikes into ties. The positioning of the instant invention so that the abutment is immediately adjacent the weight on the switch lever eliminates one of the heretofore major causes of injury to switch mechanism, and at the same time protects the operator from injury to hands and feet during the throwing of switches. Further, the instant invention is simple in construction, and extremely economical to install and use, and the invention is somewhat universal in its application in that it can be used with switch stands, especially low stands, of substantially any type.

I claim:

1. A switch lever stop of the character shown and described, consisting of a metal bar curled around near one end to provide a slightly yieldable and curvate abutment for arresting the movement of a switch lever at a predetermined position.

2. A switch lever stop of the character shown and described, consisting of substantially flat base having perforations therein adapted to receive fastening means, and a slightly yieldable abutment portion curled outwardly from the plane of the base to one side of said perforations and having the extremity thereof contacting said base, with an outwardly convex curvate portion acting as the abutment for a switch lever.

3. A switch lever stop including a substantially flat base, and an abutment portion curving upwardly and inwardly from one end of said base, the free end of said abutment portion contacting the flat base, and a weld joining said free end to said base.

4. A switch lever stop including a flat metal bar having an integral upstanding roll at one end, said bar being perforated for attaching means entirely to one side of said roll.

5. A switch lever stop including a base perforated for attaching means and an outwardly convex upstanding abutment portion of the same material as the base and disposed entirely to one side of the perforated portion, said abutment portion being of heavy stock to withstand blows of a switch lever.

6. A switch lever stop including a substantially flat tie engaging portion having an opening therein for a fastening element, and an upstanding abutment portion at one end of said flat portion and entirely to one side of said opening, the spacing between said opening and said abutment being at least two inches, said abutment being shaped to be self-supporting.
